UNITED STATES PATENT OFFICE.

BONIFACE A. GRASBERGER, OF RICHMOND, VIRGINIA.

WHEEL-HUB.

SPECIFICATION forming part of Letters Patent No. 351,910, dated November 2, 1886.

Application filed September 4, 1886. Serial No. 212,711. (No model.)

To all whom it may concern:

Be it known that I, BONIFACE ALOYSIUS GRASBERGER, of the city of Richmond, in the county of Henrico and State of Virginia, have 5 invented a new and useful Improvement in Wheel-Hubs for Vehicles, of which the following is a full, clear, and exact description.

This invention relates to vehicle-wheel hubs adapted to give a staggering arrangement to 10 the spokes of the wheel, and has for its object the securing of the greatest possible strength to the spokes without destroying the symmetry and beauty of the plain wooden hub; and the invention consists in a novel construction 15 of the hub for such purposes, substantially as hereinafter described, and pointed out in the claims.

Reference is to be had to the accompanying drawings, forming a part of this specification, 20 in which similar letters of reference indicate corresponding parts in all the figures.

Figure 1 represents a longitudinal section of the hub with the spokes in part secured therein; Fig. 2, a transverse section thereof 25 upon the line $x-x$ in Fig. 1, and Fig. 3 a detail sectional view showing a modified construction of a metal shell used in building up the hub. Fig. 4 is a side view of a portion of the hub, with the spokes in section.

30 The body of the hub is composed of an outer end wooden hub-section, A, and inner end wooden hub-section, A', arranged at a distance apart and bored, as at b , to receive the axle. These wooden hub-sections are 35 fitted within or incased by a metal shell, B B', which, as shown in Figs. 1 and 2, is made in two pieces or lengths, the outer or front portion or section, B, of the shell receiving the wooden hub-section A, and the inner or back 40 portion or section, B', receiving the other wooden hub-section, A'.

The front shell part, B, is constructed with a central tubular extension, c , on its inner end, between the two hub-sections A A', to 45 provide for its insertion within an inner flange, d , on the inner end of the back shell-section, B', as shown in Fig. 1. The shell sections B B' are united with each other by bolts or rivets e . The metal shell B B', however, incasing 50 the wooden hub-sections, instead of being made in two pieces, may be constructed in a single piece by dispensing with the rivets and constructing the two end parts of the shell with an inner flange, c' , uniting them, as shown

in Fig. 3. Whenever the rivets are dispensed 55 with, the metallic shell is constructed with divisions between every spoke to form a separate socket for each spoke; but I claim nothing new in providing the spokes with independent sockets. In any case, however, the 60 metal shell is adapted to receive the two wooden hub-sections A A' within it, and to leave a space, f , intermediately of its length all around for reception of the inner ends of the staggering spokes C C, which inner end 65 portions may either be parallel on their front and back sides, as shown in Fig. 1, and be held in place by the bolts or rivets e entering grooves within the spokes, as in other spoke-holding constructions; or, if the shell B B' is 70 of a single construction, they may be made to spread out laterally by a locking-wedge, g , as shown in Fig. 3.

To provide for the staggering disposition of the spokes, the side walls of the spoke-receiving space or recess f are made of increased thickness, or with interior projections, as at h , alternately as regards the consecutive spokes on each opposite side wall all around said recess, so as to throw each spoke alternately to 80 opposite sides.

The outer and inner end wooden hub-sections or end blocks, A A', which form the core of the hub, are turned to shape, then cut in, say, five pieces, one to be wedge-shaped, so as 85 to form a key to the whole; or they can be steamed and forced into the hub.

Having thus described my invention, what I claim as new, and desire to secure by Letters Patent, is—

1. The combination, with the shell B, having the central tubular extension, c , on its inner end, and the projections h , of the section B', having the inner flange, d , having an aperture receiving the outer end of the extension c , and projections h , alternately with those on the shell B, and the bolts or rivets e , substantially as set forth.

2. The hub consisting of the sections B B', connected by a tubular inner flange or extension, and intermediate alternating projections, h , forming hub-receiving recesses, and the wooden hub-sections A A', substantially as set forth.

BONIFACE A. GRASBERGER.
